MINGTON, DELAWARE, A CORPORATION OF DELAWARE

MOLD FOR MANUFACTURING FOOTWEAR

Application filed May 15, 1929. Serial No. 363,358.

This invention relates to an improved mold and process for manufacturing footwear. The mold and process of this invention are particularly adapted for manufacturing canvas footwear with rubber compound soles.

5 The object of the invention is to provide a shoe, preferably with a canvas upper and a rubber compound sole firmly attached thereto and vulcanized, the appearance of the shoe 10 when completed being substantially the same as that of the ordinary leather shoe, except as to the material of the upper and sole and heel.

Another object of the invention is to provide a shoe, preferably with a canvas upper 15 and a rubber compound sole firmly attached thereto and vulcanized, in which there are recesses and/or projections on the tread of the sole and/or heel. Some types of shoes with 20 canvas uppers, particularly athletic shoes, require very deep indentations in the outsole. Also, it is desirable to have recesses in the heel into which corresponding projections on 25 the mold project for more perfect vulcanization of the comparatively thick portion of material forming the heel, the pattern or 30 corrugations on the sole of the shoe forming a non-skid surface.

It is an object of this invention, therefore, 35 to provide a process whereby recesses, indentations or projections may be formed upon the tread of the sole and/or heel during the process of attaching the sole and heel to the shoe upper and to vulcanize the sole and heel during the same process.

The ordinary factory process forms the 40 outsole pattern by means of an engraved calender roll in combination with another calender roll, between which the material to be embossed is fed. It is difficult to obtain a deep indentation in the sole or heel by this means, and it is an object of this invention to provide means whereby these deep indentations may be clearly and positively obtained 45 in the tread surface of the sole and/or heel, while during the same process the shoe is vulcanized. The result attained by our improved process in this latter respect is a saving in cost, besides more perfect work, due to 50 the fact that in order to make a non-skid sole

by the ordinary factory process, hereinbefore set forth, the sole must be molded or semi-cured and subsequently stuck on to the lasted shoe with vulcanizable cement and then the whole assembly cured, whereas in the process 55 embodied in this invention, and hereinafter fully described, all of these different steps take place at the same time, or immediately in succession, during the same sequence of operations in the process.

Heretofore in manufacturing canvas footwear the rubber compound sole has been attached to the upper by a narrow strip of rubber or rubber fabric composition which is cemented around the entire edge of the 60 shoe on the outer face thereof to a height of about one-half inch, and this strip of foxing is for the purpose of securely attaching the sole to the canvas upper. The appearance, however, of a shoe made in this manner is 65 very unsightly, and in the manufacture of the shoe by the process and mold of this invention, the foxing is omitted and the outsole attached to the innersole and to the edges of the upper, (which latter are turned 70 inwardly over the innersole) by tacks and by vulcanizable cement and by very heavy pressure during the molding operation, while at the same time the rubber compound sole 75 and/or heel is provided with recesses and 80 also vulcanized.

In carrying out our improved process, the 85 canvas upper assembly, consisting of a vamp and quarter and other parts sewed together, is placed upon a last and the edges of the upper lasted over an innersole which is placed upon the bottom of the last. The inturned edges of the upper are attached to the innersole in any suitable manner. The lasted upper, together with the innersole are then removed from the last and placed upon a hollow last, or core, in a mold, the core being heated by steam or hot water. Side presser plates are then brought to bear against the 90 outer surface of the upper adjacent to the innersole and these side presser plates have beads on their inner faces which press the edge of the upper against the innersole and 95 prevent the rubber compound of the outsole 100

from being forced downwardly and into contact with the outer face of the upper.

- After pressing the side presser plates against the upper and locking them in position, an outsole of rubber composition, or any desired composition, of approximately the shape and size of the completed outsole and heel is placed between the side presser plates, the tread of the sole and heel being comparatively smooth. Then a heated sole presser plate is brought to bear against the outsole and its heel and pressed thereagainst with a heavy pressure, the presser plate having engraved upon the surface which contacts with the tread of the sole any pattern which it may be desired to impart to the sole. The surface of the presser plate which contacts with the tread of the heel may have engraved thereon recessed portions so as to obtain projections on the tread of the heel, or it may have projections thereon which will project into the heel and result in more perfectly vulcanizing the thick material of which the heel is composed, while at the same time forming recesses in the heel. The heated presser plate is left in contact with the outsole and heel, under heavy pressure, until the sole and heel are vulcanized. The sole presser plate is then released and moved out of contact with the sole and its heel and the side presser plates are moved out of contact with the upper and the shoe is then removed from the core or boot tree and from the mold, it being then completed with the sole firmly attached to the innersole and the inturned edges of the upper, and the sole and heel being vulcanized without any of the material of the sole appearing on the outer or visible face of the upper of the shoe and with the tread portion of the sole provided with recessed portions preferably in the form of a pattern to prevent skidding, and with the tread portion of the heel, where desired, provided with recesses and/or corrugations.
- The sole and heel of the shoe of this invention are formed of a rubber compound which contains vulcanizable material, and prior to the vulcanizing operation this sole and heel are comparatively yielding or plastic, so that when molded under pressure the inturned portions of the upper are first pressed into the rubber of the sole and become intermingled therewith and firmly attached thereto, so that they cannot be torn apart by any use to which a shoe may be subjected. Then as the vulcanizing process takes place, the intermingled portions of fabric and upper become integral with each other, and vulcanized together.
- If desired, the upper referred to may be lasted over the innersole and attached thereto either by tacks or by vulcanizable cement, in the latter case the inturned edges being rubbed down into close contact with the innersole and the outsole subsequently attached

to the upper and innersole by vulcanizable cement and by molding and vulcanizing the same thereon by the process, and preferably by the mold of this invention.

The invention consists in the process of manufacture hereinbefore and hereinafter described and in the mold specifically described in the following portion of the specification and as set forth in the claims.

Referring to the drawings:

Figure 1 is a plan view of our improved mold for manufacturing footwear.

Fig. 2 is a front elevation of the same.

Fig. 3 is an end elevation, and

Fig. 4 a sectional elevation taken on line 4—4, Fig. 2.

Fig. 5 is an enlarged detail section taken on line 5—5, Fig. 2.

Fig. 6 is an underneath plan of an outsole such as will be produced by our improved process and mold.

Fig. 7 is a longitudinal section taken on line 7—7, Fig. 6, with the presser plate shown in engagement with the tread surface of the outsole.

Like numerals refer to like parts in the several views of the drawings.

The mold of this invention is in duplicate, and as the two portions thereof are practically duplicates of each other, except that they are rights and lefts, a description of one portion of the mold will apply equally well to the other portion thereof.

In the drawings, 5 is the base of the mold. 6 is a core upon which the shoe is mounted during the molding and vulcanizing operation. This core is provided with a chamber 7 and an inlet port 8, to which a pipe leading to a suitable source of steam or hot water is connected. The upper end of the core 6 is shaped like a shoe which is to have the sole attached thereto and constitutes a boot tree or last. After the shoe upper 9 has been lasted in the usual manner upon a last, it is removed from the last and placed upon the core or boot tree 6 as shown in Figs. 2 and 4.

The upper 9, it will be seen, has its edges 10 folded over an insole 11 in the usual manner and these inwardly turned edges 10 are attached to the insole 11 by tacks during the lasting operation or by rubbing them or rolling them thereagainst, cement having been applied to the insole in order that the edges of the upper may adhere thereto. This operation is known as "stitching". After the shoe upper and the insole have been removed from the last upon which the upper was lasted, they are drawn up over the boot tree or form 6 as shown in Fig. 4.

A pair of oppositely disposed side presser plates 12 and 13 are fastened to arms 14 and 15 and these are duplicated at opposite ends of the shoe tree 6. These arms are pivoted at 16 to brackets 17, which are fastened to the base 5, the pivot 16 being located, as shown in

Figs. 3 and 4, below and between the centers of gravity of the presser members 12 and 13, thereby causing the force of gravity to facilitate automatic separation of the members laterally from the shoe on release thereof, and this arrangement has the advantage also that sole engaging beads 24, 24 are caused to be moved out of engagement with the sole downwardly and outwardly at an acute angle to the sole without dragging against the edges thereof.

Clamp levers 18 are pivoted at 19 to opposite ends of the side presser plate 13 and these clamp levers are each provided with a handle 20 and with a downwardly projecting arm 21 having an inclined edge 22 which, when the lever 18 is thrown downwardly toward the position it occupies in Fig. 3, will engage a pin 23 projecting from the side presser plate 12. This draws the side presser plates 12 and 13 snugly together and presses them against the outer face of the upper 9.

Each of the clamp plates is provided with an inwardly extending bead 24 which projects over the inwardly folded edge 10 of the upper and presses it downwardly and inwardly against the innersole 11 and prevents any of the rubber of the outsole from being forced downwardly into contact with the outer face 30 of the upper 9 during the molding operation.

It will be observed that the side presser plates 12 and 13 project upwardly above the upper end of the boot tree 6 forming a chamber 25 therebetween, into which the sole of rubber compound, or any other material desired, and of approximately the shape of the sole and heel which it is desired to attach to the upper of the shoe, is inserted.

Before the sole is positioned in the chamber 25 it preferably has adhesive material applied to its inner face, and the outer face of the innersole and the edges of the upper projecting thereover also have adhesive material applied thereto. The sole and heel are 45 pressed against the innersole and the infolded edges of the upper by a sole presser member 26, which consists of a plate 27 and a holder 28 provided with a chamber 29 into which steam or hot water is admitted through a port 50 30 and passes out through another port 31.

The presser member 26 is provided at one end thereof with a pair of ribs 32 and with a pair of arms 33, and between the ribs 32 and the arms 33 is an upper end of a link 34 which 55 is pivotally connected thereto by a pin 35. The lower end of the link 34 is pivoted to an eccentric 39 on a shaft 37 mounted to rock in eccentric bushings 36 positioned in the base 5. The eccentric 39 is positioned in a slot 40 60 in said base 5 and the shaft 37 is provided with a squared end 38 by means of which it can be rotated to adjust the link 34 and consequently one end of the sole presser member 26.

A stop pin 41 in the base 5 extends across 65 the slot 40 and forms a stop to limit the extent

to which the link 34 can tip outwardly, as in the position illustrated in dotted lines, Fig. 2. The arms 33 and ribs 32, together with the outsole presser member 26 all are adapted to rock upon the pivot 35 until a pin 42, which 70 extends through the arms 33 and ribs 32, engages the right hand edge of the link 34 as illustrated in dotted lines, Fig. 2. A spring 43 assists in the tipping of the sole presser member 26 from the position illustrated in full lines to that shown in dotted lines, Fig. 2.

The sole presser member 26 is forced downwardly at the opposite end from the link 34, or at the front end of the shoe, by a shaft 44 and eccentric 45 which are of the same construction and operation as the shaft 37 and eccentric 39 hereinbefore described. The eccentric 45 is positioned in the lower end of a standard 46, the upper end of which terminates in a stud 47 provided with a shoulder 48 upon which a clamp plate 49 rests, and the clamp plate is held from moving upwardly on the stud 47 by nuts 50 and 51 which have screw-threaded engagement with the stud 47. The clamp plate 49 can be rotated upon the stud 47 from the full line position illustrated in Figs. 1 and 2 to a position at right angles thereto, thus releasing the sole pressing members 26. When the clamp plate 49 is in the position illustrated in Figs. 1 and 2 it can 90 be forced downwardly against the inner ends of the sole presser members by rotating the shaft 44 with its eccentric 45.

The process of this invention is carried out and the mold is operated in the following manner:—As hereinbefore set forth, the canvas upper is manufactured in the usual manner by sewing together the parts which form the upper. This upper assembly is then placed upon a last and lasted in the usual manner, the inturned edges of the upper being attached by tacks during the lasting operation or by cement to an innersole and rubbed down or stitched. Cement is then placed upon the innersole and the inturned edges of the upper, and the upper and innersole are removed from the last and placed upon and drawn over the boot tree form 6, as shown in Figs. 3 and 4.

The side presser plates 12 and 13, which are at this time in the respective positions illustrated by dotted lines, Fig. 4, are now drawn upwardly and inwardly into the positions shown in full lines, Fig. 4, and the clamp levers at opposite ends of the side presser plates are drawn downwardly, thus locking the side presser plates together and pressing them firmly against the outer face of the upper 9, while the beads 24 press the inturned edges firmly against the innersole 11. An outsole 11' now has its inner face covered with adhesive material and is placed in the chamber 25 between the inner faces of the side presser plates 12 and 13, as illustrated in Fig. 4.

The outsole 11' is composed of rubber compound and has incorporated therein materials which render it vulcanizable, and the cement which is placed upon the innersole and upon the inner face of the outsole also contains materials which render it vulcanizable.

It will be understood that the outsole, when it is placed in the chamber 25, is not cured or vulcanized, but is in a comparatively soft or plastic state.

The sole presser members 26 are now moved downwardly by means of handles 52 from the position illustrated in dotted lines to the position illustrated in full lines, Fig. 2, and the plate 27 is brought to bear against the bottom of the sole and heel 11'. The sole pressing member 26 is then forced downwardly by rotating the shafts 37 and 44, the clamp plate 49 having been rotated 90° to the position illustrated in full lines, Fig. 2.

The outsole 11' is pressed against the in-turned edges of the upper and against the innersole with a heavy pressure and being in an uncured or unvulcanized state the in-turned edges of the upper are pressed into the outsole and the fabric or canvas becomes intermingled with the material of the outsole prior to the vulcanizing operation. The parts of the shoe are held in this position with the in-turned edges of the upper pressed into the outsole and the vulcanizing operation is then performed, due to the heat of the sole presser members 26 and plates 27 and the cores or boot trees 6.

It has been found by experiment that about ten minutes is sufficient to completely vulcanize the outsole and heel and to vulcanize it to the inturned portions of the upper, so that the upper is attached to and vulcanized in the outsole making it impossible to separate the two by any strain that may be brought to bear upon them in practice.

It will be understood, as hereinbefore set forth, that the upper may be lasted to the innersole in any suitable manner, but preferably, and especially is this the case where the upper is made of heavy canvas, the upper is lasted to the innersole by a machine and the in-turned edge portions of the upper are fastened to the innersole by tacks.

Where a box-toe is embodied in the shoe, a box-toe embodying therein cork with a gum binder is preferable and this box-toe is prepared by heating it to soften the same prior to the lasting operation. It is then inserted between the lining and the vamp of the upper and lasted in a well-known manner. When the shoe, having the box therein, is removed from the mold, as hereinbefore described, the box is soft and it is necessary to place within the completed shoe, after removing it from the mold, a toe form to preserve the shape of the shoe at the toe portion thereof, which otherwise would be badly

wrinkled and distorted due to the contraction of the stretched fabric after it has been removed from the mold.

In the foregoing description of our invention reference is particularly made to Figs. 1 to 5 in which the surface of the presser plate which contacts with the outsole is smooth.

In Figs. 6 and 7 the sole and heel are shown with projections and recesses which are imparted thereto by corresponding recesses and projections respectively on the presser plates. Referring particularly to Figs. 6 and 7, 50 is an outsole with heel 51, the same being formed of vulcanizable rubber compound. A design is imparted to the tread surface of the outsole and consists of a projecting rib 52 and recessed portions 53. The tread of the heel is provided with circular projections 54 and recesses 55. This provides a non-skid outsole.

Referring to Fig. 7, 56 is the heated presser plate corresponding to the heated presser plate 27 illustrated in Figs. 4 and 5. The presser plate 56 is provided with recesses or grooves 57, whereby the ribs 52 are formed upon the tread of the outsole and it is also provided with projections 58 whereby the recesses 53 in the tread of the outsole are produced. The heel portion of the presser plate 56 is provided with annular grooves 59, whereby the annular projections 54 are embossed upon the tread of the heel 51. The presser plate 56 is also provided with projecting pins 60 which project into the heel and form the recesses 55. These projecting pins convey heat to the interior of the heel 51 and materially assist in the vulcanizing process. In Fig. 7, 6 is the core or boot tree. 9 is the upper and 11 the innersole, as in Figs. 1 to 4 inclusive.

We claim:

1. A mold for manufacturing footwear having, in combination, a core, a pair of oppositely disposed side presser plates projecting above said core, means to press the inner faces of said presser plates against the outer face of an upper positioned on said core and lasted to an innersole, a sole presser member positioned between said side presser plates, a link, to the upper end of which said sole presser member is pivoted, means to adjust said link vertically, and means to press the free end of said sole presser member toward an outsole positioned above said core on said innersole.

2. A mold for manufacturing footwear having, in combination, a core, a pair of oppositely disposed side presser plates projecting above said core, means to press the inner faces of said presser plates against the outer face of an upper positioned on said core and lasted to an innersole, a sole presser member positioned between said side presser plates, a link, to the upper end of which said sole presser member is pivoted, means to ad-

just said link vertically, a standard positioned adjacent the free end of said sole presser member, a clamp plate rotatably mounted on the upper end of said standard, and means to force said clamp plate against the free end of said sole presser member, whereby said sole presser member may be forced against an outsole positioned above said core on said innersole.

10 3. A mold for manufacturing footwear having, in combination, a core, a pair of oppositely disposed side presser plates projecting above said core, means to press the inner faces of said presser plates against the outer face of an upper positioned on said core and fastened to an innersole, a sole presser member positioned between said side presser plates, a link, to the upper end of which said sole presser member is pivoted, means to adjust said link vertically, a standard positioned adjacent the free end of said sole presser member, a clamp plate rotatably mounted on the upper end of said standard, means to force said clamp plate against the free end of said sole presser member, and means to adjust said standard vertically, whereby said sole presser member may be forced against an outsole positioned above said core on said innersole.

25 4. Footwear manufacturing apparatus comprising, in combination, a footwear form, a plurality of edge molding members hingedly mounted for swinging movement to positions against a footwear structure on said form in fixed relation to the form to expose a determinate area of the lower portion of the footwear, and a sole molding member mounted for movement to a position to mold a sole against said exposed area of the footwear.

30 5. Footwear manufacturing apparatus comprising a pair of footwear forms, a sole pressing member for each form and means engageable with each of said sole pressing members for exerting pressure simultaneously on soles positioned on footwear structures on the two forms.

35 6. Footwear manufacturing apparatus comprising a pair of footwear forms, a plurality of presser members positionable against a footwear structure on each form, a sole pressing member for each form and means engageable with said sole pressing members for pressing them simultaneously against soles positioned on footwear structure on the two forms.

40 7. Footwear manufacturing apparatus comprising, in combination, a footwear form, means for molding a sole against a footwear structure on said form, and an edge molding member positionable against said footwear structure, said member being mounted for such swinging movement that in its footwear engaging position it tends by the force of gravity to swing away from said form.

8. Footwear manufacturing apparatus comprising, in combination, a footwear form, a support therefor, a sole molding member positionable with relation to said form by relative movement of said support and member, and an edge molding member hinged to said support for swinging movement at an acute angle with respect to the sole of a shoe on said form.

15 9. Footwear manufacturing apparatus comprising, in combination, a footwear form, a support therefor, a sole molding member positionable with relation to said form by relative movement of said support and member, and a plurality of edge molding members hinged to said support with their pivotal mountings lying in the region of the shank axis of said form.

In testimony whereof we have hereunto set our hands.

ALFRED A. GLIDDEN.
THOMAS M. KNOWLAND.
